UNITED STATES PATENT OFFICE.

ARTHUR G. HENRICKS, OF MILWAUKEE, WISCONSIN, ASSIGNOR TO PAWLING AND HARNISCHFEGER COMPANY, OF WEST MILWAUKEE, WISCONSIN, A CORPORATION OF WISCONSIN.

GRAPPLE.

1,295,163.

Specification of Letters Patent.

Patented Feb. 25, 1919.

Application filed March 15, 1915. Serial No. 14,333.

To all whom it may concern:

Be it known that I, ARTHUR G. HENRICKS, a citizen of the United States, residing at Milwaukee, in the county of Milwaukee and 5 State of Wisconsin, have invented certain new and useful Improvements in Grapples, of which the following is a specification, reference being had to the accompanying drawing, forming a part thereof.

10 This invention relates more particularly to grapples for handling bales of cotton or the like.

Its main objects are to facilitate picking up, transferring from one point to another 15 and depositing in the desired order or position, cotton or similar material put up in bales or bundles, particularly when they are bulky and heavy; to avoid tearing or mutilating the wrappings of such bales or bundles 20 or their contents; and generally to improve the construction and operation of grapples for this class of work.

It consists in the construction, arrangement and combination of parts as hereinafter particularly described and pointed out in the claims.

In the accompanying drawing like characters designate the same parts in the several figures.

30 Figure 1 is a plan view of a grapple embodying the invention; Fig. 2 is a vertical longitudinal section on the line 2—2, Fig. 1; and Fig. 3 is a diagrammatic view on a reduced scale showing the grapple in connection with a crane, a part of the front side 35 of the grapple frame being broken away.

The grapple comprises a portable frame 1, which is preferably of oblong rectangular shape, and which may be conveniently 40 made of channel bars connected at the corners by angle plates 2, which project above the frame and afford means for attachment of the ropes or cables 3 by which the grapple is suspended from a crane or hoisting 45 and transferring apparatus, as shown in Fig. 3.

The frame 1 is provided between and parallel with its side members with two ties or stringers 4, which may be made as shown 50 in Figs. 1 and 2, of channel bars riveted at the ends by angle plates to the end members of the frame. Upon these stringers is bolted an auxiliary frame or stand 5, provided midway between the ends of the frame 1 with 55 bearings 6 for a rocker shaft 7, and above

and transversely to said shaft with bearings 8 for a shaft 9. The shaft 7 is provided at its ends inside of the frame 1 with levers 10, having arms projecting equally from opposite sides thereof. Between the bearings 6 a 60 segment worm gear 11 is fixed on the shaft 7. The shaft 9 is provided between its bearings 8 with a worm 12 meshing with the gear 11, and at one end this shaft has a slip clutch driving connection. In the present 65 case this driving connection consists of a spur gear 13, loosely mounted on the shaft 9 between friction disks or jaws 14, one of which is fixed on the shaft while the other is keyed or feathered thereon and movable 70 lengthwise thereof. Between the movable disk or jaw and a washer and nuts 15 threaded on the shaft, a spiral spring 16 is interposed, the nuts, one of which is a lock nut, affording means for adjusting the tension of 75 the spring and the pressure of the friction disks or jaws on the interposed gear 13. The gear 13 meshes with a pinion 17 on the armature shaft of a motor 18, which is mounted on and bolted to the stringers 4. Two 80 transverse shafts 19 are secured in the longitudinal members of the frame 1 below, parallel with and equidistant from the rocker shaft 7. Upon the shafts 19 are pivotally mounted or fulcrumed between collars 20 85 and the side members of the frame, bell crank or angular levers 21, having their upwardly extending arms connected in pairs by links 22 with the lever arms 10 on opposite sides of the rocker shaft 7. The other 90 outwardly projecting arms of the levers 21 are provided transversely thereto with opposing tapering arcuate prongs or teeth 23, which are secured by their reduced threaded shanks in transverse holes in the ends of the 95 arms, by nuts. The prongs or teeth, which are tapered gradually from their shanks to points at their opposite ends, are curved, their center lines or longitudinal axes being concentric with the axes of the shafts 19, 100 about which they swing or oscillate, so that they will enter a bale or bundle when the grapple is closed, and will be withdrawn therefrom when the grapple is opened lengthwise, without tearing, mutilating or 105 injuring the wrapping or contents of the bale or bundle. The prongs or teeth entering the bale or bundle and being withdrawn therefrom lengthwise in curved paths exactly corresponding with the curvature of 110

the center lines of the teeth, simply make small punctures in the wrapping and contents of the bale or bundle.

The prongs or teeth 23 and the levers 21 with their operating connections are so constructed and arranged relative to the frame 1, that in the operation of the grapple the prongs or teeth will in closing move downwardly and toward each other below the bottom of the frame, which extends outwardly beyond the paths of the teeth, as shown in Fig. 3, and in opening will be withdrawn above the bottom of the frame, as shown in Fig. 2 so that the frame serves as a stripper 15 for removing bales or bundles from the prongs or teeth when they are withdrawn, as shown in Fig. 2, above the bottom of the frame.

The stand or frame 5 is formed or provided with abutments or stops 24, which by engagement with the ends of the segment gear 11 limit the movement of the grapple teeth in opening and closing, as shown in Figs. 2 and 3.

As shown in Fig. 3 the ropes or cables 3, by which the grapple is suspended at the corners of the frame 1, are connected with parallel hoisting drums 25 on the trolley 26 of a crane having a bridge 27 on which the trolley travels lengthwise and which in turn travels on overhead ways 28 transversely to the travel of the trolley.

When the grapple is provided with an electric motor for closing and opening the teeth 23, current is supplied thereto through a cable 29, looped or guided over the trolley 26 and leading from a controller 30 in the operator's cage 31, which may be suspended as shown in Fig. 3 from the trolley, but any other kind of motor or other suitable means may be employed for operating the grapple prongs or teeth.

In Fig. 3, 32 designates an electric motor for operating the hoisting drums 25, and 33 designates an electric motor for propelling the trolley 26 lengthwise of the bridge 27, these motors being supplied with current through controllers (not shown) in the operator's cage, which may be suspended from the trolley as shown, or from the bridge.

In the operation of the grapple, the prongs or teeth being withdrawn outwardly and upwardly above the bottom of the frame 1, as shown in Fig. 2, the grapple is carried in an elevated position by the crane over a bale or bundle to be elevated, and is then lowered directly upon the top of the bale or bundle by the proper manipulation of the controller in the cage 31 supplying current to the hoisting motor 32. When the frame 1 is brought to rest in proper position on the bale, the operator by the proper manipulation of the controller 30, admits current through the cable 29 to the motor 18, which through the 60 actuating connections hereinbefore described,

thrusts the prongs or teeth 23 downwardly below the frame 1 into the bale, as shown in Fig. 3, in which a bale is indicated by broken lines. After the opposing prongs are thus closed or thrust into the bale, they firmly grip the same to the frame 1 and prevent it from falling when the grapple is lifted. After the closing movement of the prongs or teeth is arrested by one of the stops 24, as shown in Fig. 3, the gear 13 slips between the friction plates or jaws 14 until current is turned off from the motor 18 by the operator at the controller 30. Current is then admitted to the hoisting motor 32 by the operator, and the bale is lifted with the grapple to the desired elevation by the simultaneous winding of the four ropes or cables 3 on the drums 25, after which it is conveyed by the crane to the desired location by the operation of the bridge and trolley motors 85 of the crane. It is then lowered with the grapple by reversing the hoisting motor 32, and after it has been deposited at the desired point the grapple is released by a reversal of the operation of the motor 18, which withdraws the prongs or teeth 23 from the bale into the position in which they are shown in Fig. 2, and in which they are arrested by the engagement of the gear 11 with the right hand stop 24, the clutch slipping until the 95 motor is stopped.

By the construction and arrangement of the parts of the grapple as shown and described, a single operator in the cage of the crane is enabled to pick up, hoist, transfer 100 from place to place, lower and deposit a bale or bundle without assistance from a helper or helpers on the floor, and since the grapple is made to grasp bales or bundles at the top instead of at the sides or ends, they may be 105 taken from and deposited in piles close together, without waste of space.

The arrangement of the prongs or teeth 23 relative to the frame 1 is such as to insure the simultaneous withdrawal of all the 110 prongs from the bale, and the positive release of the bale therefrom. The suspension of the grapple frame by four ropes or cables 3, which are simultaneously wound and unwound on the hoisting drums 25, supports 115 it with stability in a horizontal position and avoids undue swaying or swinging of the load in transferring it from one place to another, especially in starting and stopping suddenly.

The worm and worm gear drive for opening and closing the grapple, locks and holds the prongs or teeth 23 in any position in which their movement is arrested, either by the stops 24 or by the stopping of the motor 18.

The grapple may be provided with one or more, preferably two or more, symmetrically arranged pairs of prongs or teeth, and it may be constructed to simultaneously pick 130

up and carry two or more bales or bundles placed end to end or side by side.

To vary the span of the grapple for operating on more or less bales or bundles or on bales or bundles of different dimensions, provision is made for adjusting the pivot axes or fulcrums of the levers 21 toward and from each other. For this purpose the longitudinal members of the frame 1 are formed as shown in Fig. 2, with two or more sets of aligned holes 34 for the shafts 19, which may thus be spaced a greater or less distance apart, longer or shorter links 22 being provided according to the increased or diminished spacing of said shafts.

Various changes in the details of construction and arrangement of parts may be made without departure from the principle and scope of the invention as defined in the following claims.

I claim:

1. In a grapple the combination of a portable frame, a pair of rocker arms mounted in said frame on parallel pivot axes and provided with opposing pointed arcuate teeth concentric with said pivot axes, and means for simultaneously swinging said arms and teeth toward and from each other below and above the lower side of the frame, which extends outwardly beyond the paths of the teeth and serves as a stripper for the teeth.

2. In a grapple the combination of a portable frame, a pair of rocker arms mounted in said frame on parallel pivot axes and provided with opposing pointed arcuate teeth concentric with the pivot axes of the arms, and a motor mounted on said frame and adapted to swing said arms simultaneously toward and from each other below and above the lower side of the frame which extends outwardly beyond the paths of the teeth and serves to strip a bale or bundle from the teeth when the grapple is opened.

3. In a grapple the combination of a portable frame, angular levers mounted in said frame on parallel axes and provided at the free end of one arm of each lever with opposing teeth curved concentrically with the axes of the levers, a rocker shaft mounted on said frame between and parallel with the axes of said levers and provided with lever arms projecting from opposite sides thereof and connected by links with the other arms of the angular levers, and means for rocking said shaft to simultaneously swing said teeth toward and away from each other.

4. In a grapple the combination of a portable frame, a rocker shaft mounted thereon and provided with a worm gear and on opposite sides with lever arms, angular levers mounted in said frame with their fulcrums on opposite sides of and parallel with said shaft and provided at the end of one arm of each lever with tapering teeth curved concentrically with said fulcrums, links con-

necting the other arms of the angular levers with opposite lever arms on the rocker shaft, a shaft mounted on said frame transversely to said rocker shaft and provided with a worm meshing with the worm gear, and means for turning the worm shaft in opposite directions.

5. In a grapple the combination of a portable frame, angular levers fulcrumed in said frame on parallel axes and provided at the end of one arm of each lever with opposing teeth curved concentrically with said axes, a rocker shaft mounted on said frame midway above and parallel with the fulcrum axes of said levers and provided on opposite sides with lever arms which are connected by links with the other arms of the angular levers, a segment worm gear fixed on the rocker shaft, stops on the frame for limiting the oscillatory movement of said shaft and of the angular levers connected therewith, a shaft mounted on said frame transversely to the rocker shaft and provided with a worm meshing with said gear, and a slip friction clutch driving connection with the worm shaft.

6. In a grapple the combination of a portable frame, angular levers fulcrumed in said frame on parallel axes and provided with opposing teeth curved concentrically with said axes, a rocker shaft provided with a worm gear and on opposite sides with lever arms which are connected by links with said angular levers, stops for limiting the oscillatory movements of said levers, a shaft mounted on the frame transversely to the rocker shaft and provided with a worm meshing with said gear, a gear loosely mounted on the worm shaft between two friction jaws, an adjustable spring pressing one of the jaws against said gear, and a motor mounted on said frame and connected with said loose gear.

7. In a grapple the combination of a portable frame, angular levers fulcrumed in pairs on parallel axes in said frame and provided with opposing curved teeth concentric with said axes, an intermediate rocker shaft mounted on said frame parallel with said axes and provided on opposite sides with lever arms which are connected by links with the angular levers, and means for turning said shaft in opposite directions.

8. The combination of a grapple comprising a portable frame, rocker arms pivotally mounted in said frame on parallel axes and provided with opposing curved teeth concentric with said axes, a motor mounted on said frame for simultaneously swinging said arms to thrust the teeth downwardly and toward each other below the frame and to withdraw them upwardly away from each other above the bottom of the frame, which serves as a stripper for the teeth, and means for suspending and transporting and for

simultaneously lifting or lowering the frame in a horizontal position at a number of separate suspension points.

9. In a grapple the combination of a portable frame, a pair of rocker arms mounted therein with their pivot axes parallel with each other and provided with opposing curved teeth concentric with said axes, a worm gear connected with and adapted to turn said arms simultaneously in opposite directions, stops for limiting the movement of said arms in both directions, a worm meshing with said gear, and a slip clutch driving connection with said worm.

15 10. In a grapple the combination of a portable frame, rocker arms mounted in said frame on parallel axes which are adjustable toward and from each other to vary the span of the grapple and provided with opposing curved teeth concentric with said axes, and a motor mounted on said frame for simultaneously turning said arms in opposite directions toward and from each other below and above the bottom of the frame which serves as a stripper for the teeth.

11. A grapple for bales and packages, comprising a frame adapted to overlie the bale, tine carrying arms pivoted in said frame, links connected to opposite pairs of arms, rocker arms connecting each pair of links, a shaft carrying said rocker arms, and means for rotating said shaft in either di-

rection to move the tines into and out of gripping engagement with the top of the bale.

35

12. A grapple for bales and packages, comprising a frame adapted to overlie the bale, tine carrying arms pivoted in said frame, links connected to opposite pairs of arms, rocker arms connecting each pair of links, a shaft carrying said rocker arms, a gear on said shaft, and a reversible motor carried by the frame and connected to said gear to move the tines into and out of gripping engagement with the top of the bale.

40

13. A grapple for bales and packages, comprising a frame adapted to overlie the bale, tine carrying arms pivoted in said frame, links connected to opposite pairs of arms, rocker arms connecting each pair of links, a shaft carrying said rocker arms, a gear on said shaft, and a reversible motor carried by the frame, driving connections including a friction clutch between the motor and the gear, whereby the tines are moved into and out of gripping engagement with the top of the bale.

45

In witness whereof I hereto affix my signature in presence of two witnesses.

ARTHUR G. HENRICKS.
